(57) **CLAIM**

The ornamental design for a sculpted cap block, as shown and described.

DESCRIPTION

FIG. 1 is a front view of an embodiment of a cap block embodying our new design;

FIG. 2 is a rear view of the cap block of FIG. 1, the portions shown in broken lines forming no part of the design sought to be patented;

FIG. 3 is a right side view of the cap block of FIG. 1, the portions shown in broken lines forming no part of the design sought to be patented;

FIG. 4 is a left side view of the cap block of FIG. 1, the portions shown in broken lines forming no part of the design sought to be patented;

FIG. 5 is a top view of the cap block shown in FIG. 1, the portions shown in broken lines forming no part of the design sought to be patented;

FIG. 6 is a bottom view of the cap block of FIG. 1, the portions shown in broken lines forming no part of the design sought to be patented; and,

FIG. 7 is a front perspective view of the cap block depicted in FIG. 1, the portions shown in broken lines forming no part of the design sought to be patented.
